Primary Examiner—Ruth McInroy*Attorney, Agent, or Firm*—Birch, Stewart, Kolasch & Birch,
LLP[57] **CLAIM**

The ornamental design for a helmet for bicyclist, as shown.

DESCRIPTION

FIG. 1 is a front elevation of a helmet for bicyclist according to my design;

FIG. 2 is a rear elevation of the helmet;

FIG. 3 is a top plan view of the helmet;

FIG. 4 is a right-hand side view of the helmet; the left-hand side view thereof being a mirror image of FIG. 4;

FIG. 5 is a bottom plan view of the helmet; and,

FIG. 6 is a perspective view of the helmet.
